RUDOLPH HOFFMAN, OF KANKAKEE, ILLINOIS, ASSIGNOR TO SEARS, ROEBUCK AND COMPANY, OF CHICAGO, ILLINOIS, A CORPORATION OF NEW YORK.

SAFETY STARTING DEVICE.

1,190,900.

Specification of Letters Patent. Patented July 11, 1916.

Application filed April 10, 1916. Serial No. 90,073.

To all whom it may concern:

Be it known that I, RUDOLPH HOFFMAN, a citizen of the United States, residing at Kankakee, in the county of Kankakee and 5 State of Illinois, have invented certain new and useful Improvements in Safety Starting Devices, of which the following is a specification.

The object of this invention is to provide 10 improved means for insuring that both hands of the operator of a punch press, stamping press or similar machine shall be out of the danger zone during the descent of the ram.

15 In the accompanying drawings, Figure 1 is a front elevation of a punch press provided with a safety device embodying the features of my invention. Fig. 2 is a fragmental side elevation of the machine with 20 certain parts in section. Fig. 3 is a plan section on an enlarged scale, taken in the plane of dotted line 3—3 of Fig. 1. Fig. 4 is a fragmental front elevation.

The present invention is adapted for application to punch presses, stamping presses and similar machines of any standard or preferred construction. Such machines are usually arranged so that the clutch is thrown out automatically upon the completion 25 of one revolution of the main shaft. When the clutch is thrown in, the ram descends, then rises and stops. The clutch is herein shown as arranged to be thrown in by means of a bar 1 connected at its upper 30 end to the clutch mechanism and guided at its lower end in a guide 2. Fixed to the bar 1 is a back-plate 3. On the back-plate is a stud 4. The means for drawing the bar 1 downward to throw in the clutch comprises 35 devices arranged to bear against the stud 4. These devices comprise two bell crank levers 5 connected to the back-plate 3 for pivotal and downward movement. The levers 5 are arranged opposite to each other, as 40 shown in the drawings, and lie between the back-plate 3 and a front-plate 6, said plates being rigidly secured together. Each lever consists of a downwardly-extending arm 7 and a horizontal arm 8. Near the angle of 45 the bell-crank is a vertically-elongated opening 9 through which extends a stud or pin 10.

Coiled springs 11 connected to the levers 5 and to the back-plate 3 normally hold the 55 levers in such position that the lower end

walls of the openings 9 are in contact with the pins 10 and the lower arms of the levers are separated from each other and lie in contact with stop-pins 12. The levers 5 are arranged to be pivotally moved so that 60 the lower arms 7 lie in contact with each other directly above the stud 4 as shown in Fig. 4. The means for thus swinging the levers 5 comprises two hand-levers 13 pivoted at 14 (Fig. 3) to a support 15 fixed to 65 the machine frame. Each hand-lever is connected with the horizontal arm 8 of one of the levers 5 by means of a link 16. 17 are stops to limit the downward movement of the hand-levers, as will appear hereinafter. 70 Located in the horizontal plane of the hand-levers and between said levers is fixed a bar 18.

To throw in the clutch, the operator grasps both hand-levers 13 and simultaneously depresses said levers. The depression of the hand-levers first results in bringing the arms 7 of the levers 5 together above the stud 4 as indicated in Fig. 4. The continuing depression of the hand-levers causes 75 the arms 7 to bear against the stud 4 and thereby draw the back-plate 3 and bar 1 downward, thus throwing in the clutch. If the operator should endeavor to throw in the clutch by using only one hand-lever 13, the arm 7 of the lever 5 connected to said hand-lever would swing from its stop-pin 12 over to the opposite side of the stud 4, and the hand-lever would come into contact with its stop 17 before the back-plate 80 3 and the bar 1 were moved downwardly. It will be seen that in order to produce a downward movement of the bar 1, the bell-crank levers 5 must be simultaneously swung 85 into contact with each other, so as to prevent either of the arms 7 from swinging past the stud 4.

When both hand-levers 13 are simultaneously depressed, the stops 17 do not come into action, the clutch-operating devices controlled by the bar 1 serving to limit downward movement of the hand levers. 90

The stationary bar 18 located between the hand-levers 13 prevents the operator from simultaneously depressing both hand-levers 105 by laying his forearm across them.

I claim as my invention:

1. A machine having a starting member, two relatively-movable elements carried by said member, each of said elements being ar- 110

- ranged to limit movement of the other, a stud on the starting member arranged to be simultaneously engaged by said elements when their movement is thus limited, two hand-levers each connected to one of said elements, and a stationary member located between the hand-levers to prevent simultaneous depression of both hand-levers with one arm.
- 5 10 2. A machine having a starting member, two bell-crank levers each having an elongated opening therein, pins extending through said elongated openings and securing the bell-crank levers to the starting member, a stop-pin on the starting member for each bell-crank lever, spring means tending to hold the bell-crank levers in contact with the stop-pins, a stud on the starting member located between the stop-pins, and 15 means for swinging the bell-crank levers against the action of the spring means and into engagement with said stud.
- 15 20 3. A machine having a starting member, a bell-crank lever having an elongated opening therein, a pin extending through said elongated opening and securing the bell-crank lever to the starting member, a stop-pin on the starting member for the bell-crank lever, spring means tending to hold 25 the bell-crank lever in contact with the stop-pin, a stud on the starting member, means for swinging the bell-crank lever against the action of the spring means, and manually-operable means for limiting the swinging 30 movement of the lever when the lever is in alignment with the stud.
- 30 35 4. A machine having a starting member, two bell-crank levers movably supported opposite each other, a stop-pin for each bell-crank lever, springs tending to move the bell-crank levers into contact with their stop-pins, a stud on the starting member located 40 between the stop-pins, and means for swinging the bell-crank levers into contact with each other and against the stud.
- 40 45 5. A machine having a starting member, two bell-crank levers movably supported by said member, a stop-pin for each bell-crank lever, springs tending to hold the bell-crank levers in contact with their stop-pins, a stud on the starting member located 50 between the stop-pins, and means for swinging the bell-crank levers toward each other and into engagement with the stud.
- 50 55 6. A machine having a starting member, a bell-crank lever pivoted on said starting member, a stop-pin on the starting member for the bell-crank lever, a spring tending to hold the bell-crank lever against the stop-pin, a stud on the starting member arranged 60
- to be engaged by one arm of the lever, means engaging the other arm for swinging the bell-crank lever, said lever being adapted to swing to the side of the stud opposite to the stop-pin, and means to limit such swinging 65 movement.
- 65 70 7. A machine having a starting member, two relatively movable elements carried by said member, each of said elements being arranged to limit movement of the other, a stud on the starting member arranged to be simultaneously engaged by said elements when their movement is thus limited, and two hand-levers each connected to one of said elements.
- 70 75 8. A machine having a starting bar, two relatively-movable elements supported by said bar, said elements being arranged to swing into contact with each other, whereby each limits movement of the other, a stud 80 on the starting bar arranged to be simultaneously engaged by said elements when their movement is thus limited, and two hand-levers each linked to one of said elements for swinging said elements toward each other.
- 80 85 9. A machine having a starting member, a bell-crank lever pivoted on said starting member, a stud on the starting member, means for swinging the bell-crank lever, and manually-operable means to limit such 90 swinging movement when one arm of said lever is in alignment with the stud.
- 90 95 10. A machine having a starting member, two bell-crank levers movably supported upon said member, a stud on the starting member, and means for swinging the bell-crank levers into engagement with the stud.
- 95 100 11. A machine having a starting member, a stud on the starting member, two relatively-movable elements supported for lost motion with relation to the starting member, and means for simultaneously pressing both elements against the stud.
- 100 105 12. A machine having a starting member, two bell-crank levers movably supported upon said member, a stud on the starting member, and means for swinging the bell-crank levers into contact with each other and into engagement with the stud.
- 105 110 13. A machine having a starting member, two relatively-movable elements supported for lost motion with relation to the starting member, each of said elements being arranged to limit movement of the other, a stud on the starting member, and means for 115 moving said elements into engagement with the stud.

In testimony whereof, I have hereunto set my hand.

RUDOLPH HOFFMAN.
